UNITED STATES PATENT OFFICE.

PERCY R. MOFFITT, OF PAWTUCKET, RHODE ISLAND.

SPINDLE-RETAINING DEVICE.

Application filed May 4, 1928. Serial No. 275,063.

This invention relates to spindle retaining devices, and the primary object thereof is to provide a device of this character which is of simple, compact and economical construction, 5 and which can be easily and quickly manipulated to latch and release the spindle, with relation to its support.

A further object of the invention is to provide a device of this type which is composed 10 of a minimum of parts that are compactly assembled and occupy a very small space.

In the drawings:

Figure 1 is an end elevation of the invention;

15 Figure 2 is a vertical sectional view;

Figure 3 is a side elevation showing the device in operative position;

20 Figure 4 is a top plan view of Figure 2, and

Figure 5 is a top plan view of Figure 3.

Referring to the drawings, 1 indicates the spindle support and 2 the spindle, which latter is provided with a flanged portion 3 that is carried by a sleeve 4 secured to the spindle.

25 An arm 5 is suitably secured to the support 1 and may be cast integral therewith if desired, and is formed with a vertical perforation in which the lower end of a stem 7 is rigidly secured. The stem 7 has its upper end bent

30 over and downwardly to form a finger 8 which latter is spaced from the stem. A latching disk 9 is perforated at an eccentric point to receive the stem and has sliding and turning or pivotal movement thereon. The upper

35 face of the latching disk 9 is formed with a depression or socket 10 constituting a keeper in which the free end of the finger 8 is received. A coil spring 11 encircles the stem 7 and at one end seats on the arm 5, while its

40 opposite end abuts the under face of the disk 9.

In operation, and referring to the Figures 2 and 4, it will be seen that the latching disk 9 overlies the flange 3 so that upward movement of the spindle with relation to its support is limited by the latch. In this position of the parts, it will also be noted that the end of the finger 8 engages in the socket 10 and is held therein by the action of the spring

45 11. When it is desired to release the spindle it is merely necessary to depress the latching disk 9 sufficiently to disengage same from the finger 8, whereupon the latch is turned to the position of Figure 3, and upon release

50 the spring holds same against the finger 8. From the foregoing it will be seen that the

device can be easily and quickly operated by a slight depressing and turning movement of the latch and in restoring the latch to latched position, it is merely necessary to turn the 60 latch until the socket 10 registers with the finger 8, whereupon the spring will automatically effect engagement of these latter parts.

Having thus described my invention what I claim as new and desire to secure by Letters 65 Patent is:—

1. In combination with a spindle having a flanged portion and a support, an arm secured to the support and having a vertical perforation, a stem fixedly secured at its lower end in the perforation and having its upper end formed with a depending finger spaced from the body of the stem, a latching disk perforated at an eccentric point to receive the stem and slidable and turnable thereon and having its upper face formed with a depression to receive the free end of the finger to hold the disk against rotation, and a coil spring on the stem seated on the arm and abutting the under face of the disk to hold the 70 latter engaged with the free end of the finger.

2. In combination with a spindle having a flanged portion and a support, an arm connected to the support, a stem fixed to the arm and having a depending finger spaced therefrom, a latching member turnably and slidably mounted on the stem and having means to engage the finger so as to be held thereby against turning, said latching member being formed so as to overlie the flanged portion 85 when its said means is engaged with the finger thereby to prevent upward movement of the spindle, and a coil spring on the stem seated on the arm and engaged with the latching member to hold the latter with its said means 90 engaged with the finger.

3. In combination with a support and a spindle having a ledge, a vertical stem on the support, a latching disk having an eccentric perforation slidably and turnably received 100 on the stem and having a keeper on its upper side face, a member on the stem engaging the disk and releasably received in the keeper to hold the disk against outward sliding and also against rotation on the stem, and a 105 coil spring for holding the disk against said member, the keeper being disengageable from said member by depression of the disk.

4. In combination with a support and a spindle having a ledge, a vertical stem on the support, a latching member slidably and turnably mounted on the stem and having a keep-

er, means on the stem engageable with the member and with the keeper to hold the member against sliding movement out of engagement with the stem, and against turning movement thereon, and spring means to releasably hold the member engaged with said means on the stem.

5. In combination with a support and a spindle having a ledge, a vertical stem on the support, a latching member slideable and turnable on the stem and having a keeper on its

upper face, means carried by the stem and engageable with said member and with the keeper to hold the member against sliding movement out of engagement with the stem and against turning movement thereon, and means engaging the member to releasably hold the same engaged with said first named means.

15 In testimony whereof I have signed my name to this specification.

PERCY R. MOFFITT.
